UNITED STATES PATENT OFFICE.

MAURICE C. FRANKENSTEIN AND JOSEPH W. FRANKENSTEIN, OF PITTSBURGH,
PENNSYLVANIA.

GLOVE.

Application filed January 7, 1922. Serial No. 527,572.

To all whom it may concern:

Be it known that we, MAURICE C. FRANKENSTEIN and JOSEPH W. FRANKENSTEIN, citizens of the United States, residing at Pittsburgh, in the county of Allegheny and State of Pennsylvania, have invented certain new and useful Improvements in Gloves, of which the following is a specification.

This invention relates to improvements in gloves, and the object thereof is to provide a glove, constructed in a manner as herein-after set forth, having re-inforced portions whereby the wearing qualities of the glove are prolonged and the same rendered more impervious to the passage of heat when used by furnace workers and kindred occupations.

Further objects of the invention are to provide a glove of the character stated which is simple in its construction and arrangement, strong, durable and efficient in its use, and comparatively inexpensive to manufacture.

With these and such other objects as may hereinafter appear, the invention consists of the novel construction, combination and arrangement of parts herein described, and illustrated in the accompanying drawing, wherein is shown an embodiment of the invention, but it is to be understood that changes, variations and modifications may be resorted to which come within the scope of the claim hereunto appended.

In the drawing forming a portion of this specification and wherein like numerals of reference designate corresponding parts throughout the several views:—

Figure 1 is a front view of a glove in accordance with the invention.

Figure 2 is a rear view thereof.

Figure 3 is a front view of a modified form of the glove.

Referring in detail to the drawing 1 denotes the body portion of the glove provided with a cuff 2 of the usual construction.

The back 3 of the body portion 1, with the exception of the index finger 4, is constructed from a single ply of material, but the front 5 of the body portion of the glove,

including the rear portion of the index finger 4 and the front of the thumb member 6, is formed from several plies of material. These several plies of material are secured together with the transverse stitching 7.

As the index finger 4 of the glove is at all times subjected to the most wear, the entire re-inforcement of this member will obviously prolong the life of the glove.

The manner of stitching 7 will serve to hold the several plies of material in position even after the outer ply has been worn through from use.

In the modification shown in Figure 3 the back of the thumb 6 is also formed from several plies of materials and stitched, as indicated at 8. This construction is primarily designed for use of furnace workers and the like, where the workmen are exposed to great heat. In grasping an implement the forward portion of the glove including the index finger and thumb are nearest the source of heat in such work, and the double plies of material in our improved glove construction will serve to prevent penetration of heat to the most exposed part of the hand.

What we claim is:—

A glove having its front formed of a plurality of plies of material and further having the backs of the index finger and thumb thereof formed of a plurality of plies of material, the plurality of said plies of material forming said front being secured together by a plurality of rows of stitching, each of said rows extending transversely in a line of flexure of the glove when in use, and said plies of material forming the backs of the index finger and thumb secured together by stitching extending in alignment relatively to the rows of stitching securing the plies forming the front of the glove, substantially as described and for the purpose set forth.

In testimony whereof we affix our signatures.

MAURICE C. FRANKENSTEIN.
JOSEPH W. FRANKENSTEIN.
